Atty's.*

UNITED STATES PATENT OFFICE.

GEORGE LANE, OF POUGHKEEPSIE, NEW YORK, ASSIGNOR TO LANE BROS. CO., OF POUGHKEEPSIE, NEW YORK, A JOINT STOCK ASSOCIATION OF NEW YORK.

LIFTING-JACK.

1,320,244.

Specification of Letters Patent.

Patented Oct. 28, 1919.

Continuation of application Serial No. 114,426, filed August 11, 1916. This application filed July 11, 1918.
Serial No. 244,463.

To all whom it may concern:

Be it known that I, GEORGE LANE, a citizen of the United States, residing at Poughkeepsie, New York, have invented certain new and useful Improvements in Lifting-Jacks, of which the following is a specification, this application being a continuation of an application filed by me on the 11th day of August, 1916, Serial Number 114,426.

10 My present invention relates to improvements in lifting jacks adapted more especially for use in connection with motor vehicles, and is designed as an improvement upon the jack disclosed in Letters Patent No. 15 1,181,395, granted to me on the 2nd of May, 1916.

In devising the present invention I have aimed to simplify the construction by eliminating certain parts; to secure a positive motion of the contact pin or device in both directions by the operator instead of a spring action one way; to eliminate the constant urging of the handle backward by the spring and the consequent tendency of its 25 getting into an intermediate position, and further to provide a construction which will compensate for commercial variations and render unnecessary alterations in the jack.

A still further object is to provide a construction in which interchangeable handle bars may be used so as to effect the reversal of the jack by either a bodily shift of the handle bar in the socket member, or by the movement of a side rod carried by the handle 35 bar as preferred by the customer.

With these and other objects in view the invention includes the novel features of construction and arrangement and combination of parts hereinafter described, my said invention being defined by the appended claims.

An embodiment of the invention is illustrated in the accompanying drawing, in which,

45 Figure 1 is a sectional elevation of a sufficient portion of a jack to illustrate my invention.

Fig. 2 is a detail view of a handle bar with side rod control.

50 Fig. 3 is an end view of the actuating lever with handle bar or lever of Fig. 2 shown in place in section.

Fig. 4 is a similar view with a shiftable handle in place in the socket, and,

Fig. 5 is a view similar to Fig. 1 with the 55 shiftable handle in place.

Referring by reference characters to these drawings, the standard 2, lifting bar 3 and lifting and retaining dogs 5 and 4 are shown as constructed and arranged to be 60 operated as in my aforesaid patent, the lifting and retaining dogs being connected by the springs 13 and 14 with the bell crank levers 11 and 12 mounted alongside the actuating lever 6, and having their contact 65 portions pressed toward each other by a common spring C.

Actuating lever 6 is provided with a socket to receive a handle bar of material length to enable the jack to be placed in 70 position without crawling under the car, which handle is retained in the socket by a spring dog 19.

In Fig. 2 is shown a handle bar 7 provided with a longitudinally shiftable rod 8, 75 guided in suitable eye 8^a at the side of the handle bar and having an angularly turned end 8^b projecting through an elongated slot in the handle bar and held therein by a washer and pin 8^x, Fig. 2, or other suitable 80 means. This projecting end 8^b is designed in one position of the rod, (shown in full lines in Fig. 1) to contact with the bell crank levers alternately as the actuating lever is operated, and thus effect the lowering of the 85 lifting bar. It will be understood that the contact pin, when the handle bar is in position, projects through a cut away portion in the side of the actuating lever. Shifting of the rod to another position moves the end 90 or contact portion 8^a beyond the range of said bell crank levers, as shown in dotted lines at b' in Fig. 1, whereby the pawls 4 and 5 operate to effect the step by step raising 95 of the lifting bar.

Instead of carrying the contact piece on a separate rod slidably mounted on the handle bar, I may form said contact piece as a permanent or integral part thereof, as shown in Figs. 4 and 5 so that the reversal of the 100 jack is effected by the bodily or endwise shift of the handle bar in the socket.

In this form I retain the handle bar 7^a in the socket of the actuating lever by the

same spring pressed pin 19^a but the handle bar is provided with two approximately V-shaped notches 18^b and 18^c so as to render it capable of a lengthwise movement in the 5 socket to either of two positions determined by the engagement of the dog with one or the other of said notches as in my aforesaid patent, and provide said handle bar with a rigid pin or projection *a*, which in one position 10 of the handle bar in the socket will strike the bell crank to effect the lowering, and in the other position will be out of the range of said bell cranks, the pin, when the handle is in position projecting through the 15 cut-away portion 6^a of the actuating lever.

The two opposed longitudinal grooves *b*^{''} in the walls of the socket enable either of the forms of handle above described to be used in the same jack according to the 20 preference of the customer. If desired the handle bar with rigid pin may be inserted in inverted position or with the pin on the left side so that the pin will be ineffective with respect to the bell cranks. This may 25 be desirable in some instance where reversal of the jack is not desired. In such case the opposite edge of the handle bar would be provided with a notch to receive the dog 19^a as indicated at 18^d.

30 From the foregoing description it will be apparent that I have produced a simpler and more durable form of jack, having eliminated the rocking member 21 of my previously patented construction and the 35 spring for actuating the same, resulting also in corresponding reduction in cost of manufacture.

Furthermore the shifting of the contact 40 piece is positive in both directions and not dependent on any spring action, whereby I avoid all danger of failure of the jack to reverse properly due to weakness of the spring which may arise from several causes, as for example, insufficient initial strength, 45 loss of force due to change of shape or drawing of temper under the heat used in enameling, or weakening under prolonged use.

I also avoid in my present construction 50 any danger of the handle coming to rest in an intermediate position as sometimes occurs where there is some play or looseness of parts due to inequalities in manufacture when the spring in my patented construction 55 referred to would urge the handle bar backward far enough to bring the pin or contact device into neutral or ineffective position.

Still another advantage of carrying the 60 contact member on the handle bar is that I can select the handle bar best fitted for each particular jack and thus compensate for slight variations in manufacture which might otherwise require alterations in the 65 jacks or handle bars.

Having thus described my invention, what I claim is:

1. A jack comprising a standard, a lifting bar guided therein, lifting and retaining pawls, a lever pivoted in the standard and provided with a socket for receiving an operating bar, devices movably supported from the standard for controlling said pawls and a controller for said devices shiftable into and out of actuating position 70 in reference thereto, said controller being carried independently of the lever, and acting directly upon the said devices when in actuating position, and an operating bar having an end adapted to be held within the 75 socket in the lever.

2. A jack comprising a standard, a lifting bar, lifting and retaining pawls, a lever mounted in the standard having a socket for receiving an operating bar, devices supported from the standard for controlling the operation of the pawls, a removable operating bar having an end adapted to be held in the socket in the lever and a controller carried by said operating bar, and movable into and out of actuating position 85 in reference to said devices, said controller when in actuating position acting directly upon said devices.

3. A jack comprising a standard, a lifting bar, lifting and retaining pawls, a lever mounted in the standard having a socket for receiving an operating bar, devices supported from the standard for controlling the operation of the pawls, a removable operating bar having an end adapted to be held in the socket in the lever and a controller carried directly by said end and movable with 90 said operating bar into and out of actuating position in reference to said devices, said controller when in actuating position acting directly upon said devices.

4. A jack comprising a standard, a lifting bar guided therein, lifting and retaining pawls, a lever pivoted in the standard and provided with a socket for receiving an operating bar removably, said socket having centrally arranged opposed grooves in its side walls, devices movably mounted adjacent the lever for controlling said 110 pawls, and a projection carried by the handle bar and slideable into either of said grooves on insertion of the handle bar, said projection when lying in one of the grooves serving as a controller for said devices and 105 being shiftable into and out of actuating position in reference thereto.

5. A jack comprising a standard, a lifting bar guided therein, lifting and retaining pawls, a lever pivoted in the standard 125 and provided with a socket for receiving an operating bar removably, said socket having centrally arranged opposed grooves in its side walls, devices movably mounted adjacent the lever for controlling said pawls, 130

and a projection carried by the handle bar and slidable into either of said grooves on insertion of the handle bar, said projection when lying in one of the grooves serving as 5 a controller for said devices and being shiftable into and out of actuating position in reference thereto, means for holding said handle bar in either of two determined positions when the contact projection lies 10 in one groove and means for holding it in a single position when inverted with the projection in the other groove.

6. A jack comprising a standard, a lifting bar, lifting and retaining pawls, a lever 15 mounted in the standard having a socket for receiving an operating bar removably, devices mounted adjacent the lever for controlling the operation of the pawls, an operating bar having an end adapted to be 20 held in the socket in the lever, a lateral projection carried by said end, the walls of said socket having grooves either of which is adapted to receive said projection, a

spring pressed beveled pawl carried by said lever and projecting into the socket, one 25 edge of said handle bar having a single pawl receiving notch and the other a pair of notches.

7. A jack comprising a standard, a lifting bar, lifting and retaining pawls, a lever 30 mounted in the standard having a socket for receiving an operating bar, devices supported from the standard for controlling the operation of the pawls, an operating bar having an end adapted to be held in the 35 socket in the lever and a controller carried by said operating bar, and moved by the movement of said operating bar into and out of actuating position in reference to said devices, said controller when in actuating position acting directly upon said devices.

In testimony whereof, I affix my signature.

GEORGE LANE.
